UNITED STATES PATENT OFFICE.

WILLIAM LINVEL HENRY, OF LOUISVILLE, KENTUCKY.

MANIFOLD RECEIPT, WAY-BILL, AND DELIVERY-RECORD BOOK FOR EXPRESS COMPANIES.

1,221,988.

Specification of Letters Patent. Patented Apr. 10, 1917.

Application filed October 14, 1912. Serial No. 725,629.

To all whom it may concern:

Be it known that I, WILLIAM LINVEL HENRY, a citizen of the United States of America, residing at Louisville, in the county of Jefferson and State of Kentucky, have invented certain new and useful Improvements in Manifold Receipt, Way-Bill, and Delivery-Record Books for Express Companies, of which the following is a specification, reference being had to the accompanying drawings.

This invention relates to improvements in receipt and record forms and particularly to combined manifold receipt and record forms for use by common carriers, such as express companies; and an object of this invention is to provide a combined manifold receipt, way-bill and delivery record form which will be simple in its make-up, susceptible of being readily understood by those persons for whose use it is intended, convenient in manipulation and use and particularly well adapted for filing, record and accounting purposes. Another object of this invention is to provide a combined form of the character hereinbefore referred to which will give auditors, route agents and like officials an absolute and positive check upon the local agents within the territory under their charge and will also afford a local agent an absolute and positive check upon the drivers, way-bill clerks and receiving clerks connected with his office, and which will assist the agent (or his cashier) in making settlement with the driver and will afford a check on the statement used in balancing his account. A third object of this invention is to reduce the amount of clerical work connected with the receiving, transportation and delivery of goods by common carriers, such as express companies. A fourth object of this invention is to provide a combined form of the type hereinbefore alluded to which will take the place of separate receipts, way-bills, delivery sheets and the stickers of various kinds now commonly used and which will thereby effect a substantial saving in the amount of stationery now used by express companies in the transaction of their business.

In the drawings illustrating the principle of this invention and the best mode now known to me of applying that principle, Figure 1 is a central longitudinal section

through a binder or cover and the pads of 55 forms carried by the same; Fig. 2 is a perspective view of the combined triplicate receipt, way-bill and delivery record; Fig. 3 is a plan view of the way-bill; Fig. 4 is a plan view of the delivery record; Fig. 5 60 shows a modification, and Fig. 6 is a plan view of the right hand end of Fig. 2, the corners of some of the leaves being turned up to show the gummed surface of the sticker. 65

Referring particularly to Fig. 2, the topmost sheet or blank form A consists of the stub A^x, the receipt proper A^{''} and the sticker A['], the receipt proper being separated from the stub and sticker by lines 70 of perforations, as shown. This topmost form A is to be filled out by the driver or receiving clerk, who takes the package from the consignor. The driver or receiving clerk, in filling out the receipt proper A^{''}, 75 inserts the date in the space at a'', the value (if given) at b'', the name of the consignor at c'', the name of the consignee at d'', the address of the consignee at e'', the number of packages and their alleged contents at f'', 80 and signs the receipt for the company at g''. If the goods are sent collect on delivery, the amount to be collected is filled in at h''. The driver (or receiving clerk) at the same time fills out also the stub A^x inserting the 85 date at a^x, the name of the consignor at c^x and the name and address of the consignee at d^x, and he also at this same time of receiving the goods fills out the sticker A['], inserting the date at a', the name of the consignor 90 at c', the value (if given) at b' and, if the goods are sent collect on delivery, he fills in the amount to be collected at h'. He then detaches the sticker A['] from the receipt proper A^{''} by tearing it off along the line 95 of perforations i and pastes this sticker A['] to the package. He then detaches the receipt proper A^{''} from the stub A^x by tearing it off along the line of perforations i' and gives this receipt to the consignor. The 100 stub A^x is left in the driver's book as a record. On arriving at the express company's office, the driver turns in the package, together with the combined way-bill and delivery sheet hereinafter more particularly 105 described. Underneath the receipt proper A^{''} lies the way-bill form B (Fig. 3) the upper half of which is substantially identi-

cal in form with the upper half of the receipt proper A''. Between the way-bill form B and the receipt proper A'' there is interposed a piece of carbon paper (or manifold paper) which is so laid or arranged that, when the driver fills out the receipt proper he also fills out on the way-bill the date, the value of the goods, the name of the consignor, the name and address of the consignee, the number of pieces and their alleged contents and, if the goods are sent collect on delivery, the amount to be collected. The way-bill form contains also spaces as follows: The space *j* for the insertion of the weight; the space *k* for the amount paid; the spaces *m* and *n* for the correction of the amount charged, the amount to be added being inserted in the space *m* and the amount to be deducted being inserted in the space *n*. If the goods are paid beyond a certain point, that fact is noted in the space *o*. The number of the trunk in which the goods are packed is inserted in the space *p* and the routing written out in the space *q*. If there is to be a transfer, that fact is recorded in the space *r*. The place to which the package is way-billed is set forth at *s*. The completing of the filling-out of the way-bill is done by the way-bill clerk, who also fills out (or directs the filling-out of) the spaces at *q'* and *s'* on the sticker A', relating to the routing and the point to which the package is way-billed, respectively. At one end of the way-bill there is provided a space marked "First Messenger" the use of which space is as follows: In case the common carrier operates over several lines from the initial point, it is necessary in order to check tonnage properly, to have the first messenger stamp his route on the face of the way-bill and this is done in the space *t* just referred to. This record of the first messenger on the face of the way-bill is for the use of the auditor and receiving agent. All other messengers stamp their routes on the back of the way-bill, commencing at the left-hand end.

Formed in one with the way-bill B is the delivery sheet C which is folded along the line of perforations *i''* and which is the lowermost of the three sheets A, B, C. The delivery sheet C may be said to consist of three parts, namely, the delivery sheet proper C'', the sending-office stub C^x and the consigned's receipt C'. Interposed between the way-bill sheet B and the delivery sheet C is a piece of carbon (or manifold) paper which overlies the delivery-sheet proper C'' and the sending-office stub C^x. It is to be observed that no part of the way-bill sheet overlies the sending-office stub C^x; and, by looking at Fig. 1, it will be seen that the driver's stub A^x of the receipt sheet A must overlie the sending-office stub C^x of the delivery sheet C. Again, the sticker A' overlies the "first mes-

senger" space *t* at the outer end of the way bill; and this "first messenger" space *t* lies directly above the consignee's receipt C' at the outer end of the delivery-sheet C; but no part of either sheet of carbon-paper extends below the sticker A' or below the first messenger space *t*. The carbon-paper between the receipt sheet A and the way-bill sheet B does, however, extend below the driver's stub A^x and over the sending-office stub C^x, with the result that when the driver fills out the date, the name of the consignor and the name and address of the consignee on the driver's stub A^x, in his book, he fills out the corresponding spaces *a^x*, *c^x* and *d^x* on the office stub C^x. Furthermore, the delivery-sheet proper C'' is a duplicate of the way-bill sheet B, except for the first messenger space *t* at the outer end of the latter; and, when the driver makes out the receipt proper A'', he fills in not only the upper half of the body of the way-bill sheet B but also the upper half of the delivery sheet proper C''; and, when the way-bill clerk fills in the lower portion of the way-bill sheet and thereby completes the same, he simultaneously fills in the lower portion of the delivery-sheet proper C'' and completes it. The way-bill clerk fills in on the sending-office stub C^x the weight and charges in the spaces *u^x*, *v^x*, respectively; and he then detaches this sending-office stub C^x from the delivery sheet C and retains the office stub C^x at the sending office as a record. Each of the parts A', A'', A^x, B, C', C^x, which are separable from one another, are marked with the same identifying number *w*. The way-bill sheets B and the delivery sheets C, (except the sending-office stubs C^x, which are detached along the line of perforation *i^x* and retained by the way-bill clerk at the sending office) will be set up in numerical order at the sending office and will be sent forward and delivered with the freight to the messenger, whose duty it is to check the way-bills by the number *w* on the package stickers A' against the number *w* on the way-bill B. After this has been done, the messenger will proceed again to set his bills up in numerical order, in station (or delivery). Transfer clerks and the receiving office will check in the same manner except that the point the shipment is from will have to be called off, as well as the numbers *w*. When the goods will have been received at the receiving office, the receiving agent will check his freight and detach the delivery-sheet C'' from the way-bill and make prompt delivery, filing the delivery-sheet C'' in his office, after delivery has been made, as a record and forwarding the way-bill B to the auditor with the usual statement at the settlement period. If at the receiving office more than one driver is to make delivery, the delivery-sheets for each driver should be tabulated, the table showing the way-bill number, where

it is from and the amount to be collected, if any. This will assist the cashier (or the agent) to make proper settlement with the driver and will act as a check on the statement to balance his accounts. Upon making delivery, the consignee is required to sign and date the consignee's receipt C' at the outer end of the delivery-sheet. The delivery-sheet with the consignee's receipt thereon is then returned by the driver to the receiving office and is there filed for record, as above stated.

Each way-bill B is to be reported to the auditor on an abstract daily, stating whether the way-bill is made void or the freight transferred to another company to start transportation. If a way-bill B is made void, the receipt is taken on the delivery-sheet, which is filed as a receipt at the office making the transfer.

The drawings show a form for use in case the package is sent with the charges prepaid, as is indicated by the word, Paid, printed at x ; but in case the package is sent with charges to be collected from the consignee, the word, Collect, is printed at x , instead of the word, Paid; and, moreover, the form is printed upon paper of a different color. Again, on the way-bill form B and the delivery sheet C, the words, "Paid beyond," are omitted and the space containing the word, Paid, and lying between the spaces containing the words, "Weight" and "Add," respectively, is divided into two spaces one of which contains the word, Advance, and the other of which contains the word, Collect, as is illustrated in Fig. 5, at k' and o' , respectively.

The forms are numbered consecutively and are bound by a suitable backing y into pads z containing any convenient number of forms, as fifty forms or one hundred forms. The pad is carried in a suitable casing or binder 2 the back cover 3 of which is provided with a pocket 4 into which may be slipped the tongue 5 with which the pad is provided. In this way the driver may use indefinitely the same binder or holder and may replace one pad by another, as occasion may demand.

With reference to the combined structure and use of my invention it may be said, in brief, that this manifold receipt and record comprises a receipt form, a way-bill form and a delivery sheet form, that the receipt form and the delivery form each have a stub at each end and that each form as well as the stubs have certain corresponding printed matter, as described, which may be briefly summed up as appropriate registering indicia; that the sheets are so arranged that one lies under the other, the way-bill form being arranged to lie between the other forms and being integral with and detachably secured to the delivery sheet form; that

the way-bill form extends only to the stub adjacent the binding end which may be termed the inner stub; and that the receipt is provided with a driver's stub which has appropriately designated spaces for the reception of the driver's record of the shipment.

Or, to recapitulate more briefly yet with reference to the structure, that the invention, as illustrated, comprises two sheets, each sheet being composed of divisions with printed indicia on each sheet which registers with corresponding indicia on the other sheet; that the lower sheet has two leaves, the upper one of which is detachable from and shorter than the lower one, so that it does not cover the inner end or inner stub end of the lower sheet.

I claim:

1. A combined manifold receipt and record form, comprising a top sheet with stubs at each end, the right end stub being detachable from the stop sheet and the top sheet detachable from the left hand stub, a folded leaf lying beneath the top sheet, one of the folds being detachable from the other folds, the upper part of the folded leaf being shorter than the lower part of the folded leaf, and indicia printed on the several sheets and stubs and registering when the sheets and stubs are superposed.

2. A combined manifold receipt and record form, comprising two sheets, each sheet composed of similar divisions with printed indicia on each division registering with printed indicia on the opposing divisions, the lower sheet having two leaves, the upper one of which is detachable from and shorter than the lower one so that it does not cover the left hand end division of the lower sheet.

3. A combined manifold receipt and record form, comprising a top sheet, with a detachable stub at the right hand end and a stub at the left hand end from which the top sheet can be detached, the stub at the right end being gummed to form a sticker to be applied to a package, and a folded leaf provided with a left-hand stub and detachable from the left hand stub and lying beneath the top sheet, one of the leaves of the folded sheet being shorter than the other leaf so that it does not cover the left-hand stub.

4. A combined manifold receipt and record form, comprising a receipt form, a way-bill form and a delivery sheet form, the receipt form and the delivery form being provided with stubs at each end having appropriate registering indicia, and a way-bill form arranged to lie between the other forms and detachably secured to the delivery sheet portion and extending only to the left hand stub attached thereto.

5. A combined manifold receipt and rec-

ord form, comprising a receipt form, a way-
bill form and a delivery form being pro-
vided with stubs at each end having appro-
priate registering indicia, the way-bill form
5 being arranged to lie between the other
forms and being integral with and detach-
ably secured to the delivery sheet form and
extending only to the left hand stub at-
tached thereto, the receipt form being pro-
10 vided with a driver's stub having appro-

priately designated spaces for the reception
of the driver's record of the shipment.

Signed at Louisville, Kentucky, this 8th
day of October, A. D. 1912, in the presence
of the two undersigned witnesses.

WILLIAM LINVEL HENRY.
